UNITED STATES PATENT OFFICE.

LORETO P. ALONZI, OF CHICAGO, ILLINOIS, ASSIGNOR TO ALONZI FURNITURE CO.,
OF CHICAGO, ILLINOIS, A CORPORATION OF ILLINOIS.

DESIGN FOR A RADIOCABINET.

Application filed May 13, 1929. Serial No. 31,207. Term of patent 3½ years.

To whom it may concern:

Be it known that I, LORETO P. ALONZI, a citizen of the United States, residing at Chicago, in the county of Cook and State of Illinois, have invented a new, original, and ornamental Design for a Radiocabinet, of which the following is a specification, reference being had to the accompanying drawing, forming a part thereof.

The figure is a perspective view of a radio cabinet showing my new design.

I claim:

The ornamental design for a radiocabinet as shown.

LORETO P. ALONZI.
